(57) **CLAIM**

The ornamental design for tire, as shown and described.

DESCRIPTION

The patent or application file contains at least one drawing executed in color. Copies of this patent or patent application publication with color drawing(s) will be provided by the Office upon request and payment of the necessary fee.

1. Tire

1.1 : Front

1.2 : Left

1.3 : Perspective

1.4 : Enlarged

The use of the present design product: the design product is used for tires; the design gist of the present design product: the pattern, shape, or combination thereof shown in the each view, wherein, the pattern is repeated consistently throughout the entire perimeter of the tread; the picture or photo best showing the design gist of the present design product: perspective view; the rear view is the same as the front view after being rotated 180 degrees clockwise, so the rear view is omitted; the left view and the right view are in a mirror image relationship with respect to the vertical direction, so the right view is omitted; the top and bottom views are the same as the front view, so the top and bottom views are omitted; the red box with the indication "A" shown in reproduction 1.1 is an enlarged view of the tire shown in reproduction 1.4.
